United States Patent Office.

GEORGE BRABROOK, OF TAUNTON, MASSACHUSETTS, ASSIGNOR TO REED
AND BARTON, OF SAME PLACE.

Letters Patent No. 75,726, dated March 24, 1868.

NAME-PLATE FOR COFFINS, &c.

The Schedule referred to in these Letters Patent and making part of the same.

TO ALL PERSONS TO WHOM THESE PRESENTS MAY COME:

Be it known that I, GEORGE BRABROOK, of Taunton, in the county of Bristol, and State of Massachusetts, have invented a new and useful Improvement in Name-Plates for Coffins or Doors; and I do hereby declare the same to be fully described in the following specification, and represented in the accompanying drawings, of which—

Figure 1 is a front view, and

Figure 2 a vertical and transverse section of a name-plate, provided with my invention, the nature of which consists, mainly, in the arrangement of such name-plate, a spring and a picture-frame for holding a photograph or miniature of a person.

In the drawings, A denotes a name-plate, such as is commonly used on a coffin to indicate the name, age, &c., of a deceased person. From the upper edge or part of such plate there is an extension, B, having an opening, a, and being recessed on its back, as shown at b, to receive a glass plate, c, and a photograph, d. A spring, e, fixed to the back of the name-plate, presses on the picture, so as to hold it and the glass plate in place, the spring being curved, so that when the name-plate is screwed upon a coffin, the spring may be crowded with great force against the picture, so as to hold it and its glass plate firmly in place.

I claim the arrangement of the name-plate, the spring, and the picture-frame, the whole being substantially as set forth.

Witnesses:

WILLIAM W. SWAN,
JOSEPH H. RINES.

GEORGE BRABROOK.
